UNITED STATES PATENT OFFICE.

VICTOR A. NELSON, OF SEATTLE, WASHINGTON.

DESIGN FOR A COMBINED PINCH-BAR AND NAIL-PULLER.

52,960.

Specification for Design.

Patented Feb. 4, 1919.

Application filed September 20, 1918. Serial No. 255,002. Term of patent 7 years.

To all whom it may concern:

Be it known that I, VICTOR A. NELSON, a citizen of the United States, and resident of Seattle, county of King, and State of Washington, and whose post-office address is 725 West Spokane street, Seattle, Washington, have invented a new, original, and ornamental Design for a Combined Pinch-Bar and Nail-Puller, of which the following is a description, reference being had to the accompanying drawing, forming part thereof.

In the drawing, the figure represents a perspective view of my new design.

I claim:—

The ornamental design for a combined pinch bar and nail puller as shown.

VICTOR A. NELSON.
